UNITED STATES PATENT OFFICE.

MARTIN CHRISTENSEN, OF RACINE, WISCONSIN.

CONVEYER FOR BOOK-STITCHING MACHINES.

1,140,734.

Specification of Letters Patent. Patented May 25, 1915.

Application filed April 24, 1913. Serial No. 763,207.

To all whom it may concern:

Be it known that I, MARTIN CHRISTENSEN, a citizen of the United States, and a resident of Racine, in the county of Racine and

5 State of Wisconsin, have invented new and useful Improvements in Conveyers for Book-Stitching Machines, of which the following is a description, reference being had to the accompanying drawings, which are a part of this specification.

10 This invention relates to improvements in conveyers for book stitching machines in which groups of leaves of books or pamphlets are placed on a moving endless belt which is adapted to carry the leaves in successive order from the point of feed to the stitching mechanism where they are fastened together by the stitches or staples.

15 In ordinary machines of this type now in use the leaves are folded in V-formation and placed in groups or sets upon an inverted fixed V-shaped rail which is provided with a movable endless chain belt having projecting fingers which engage the groups of leaves and slide them along the rail to the stitching mechanism. This manner of feed was found objectionable in that the groups of leaves in sliding along the track would change their relative position with relation 20 to each other, due to frictional contact with the fixed track, so that when they arrived at the stitching mechanism they would be disarranged with the result that when stitched the different leaves of a book will not register with each other and the work is not satisfactory.

25 A further objection to the old manner of feed is that some of the leaves which rested directly upon the fixed track would become soiled by the rubbing contact with the track and as the soiled leaves would not be noticed until after they were bound with the other leaves the value of the whole book would be lessened.

30 45 It is one of the objects of the present invention to provide a conveyer for book stitching machines which will overcome the before mentioned objectionable features and feed the groups of leaves in regular order 40 without the liability of disarranging or soiling the leaves.

45 55 A further object of the invention is to provide a conveyer for book stitching machines in which the track for holding the leaves is combined with the endless conveyer and moves therewith.

A further object of the invention is to provide a conveyer for book stitching machines which is of simple construction, is strong and durable and is well adapted for 60 the purpose described.

With the above and other objects in view, the invention consists of the improved conveyer for book stitching machines and its parts and combinations as set forth in the 65 claims, and all equivalents thereof.

In the accompanying drawing in which the same reference characters indicate the same parts in all of the views: Figure 1 is a side view of a portion of the frame of a 70 book stitching machine provided with the improved conveyer; Fig. 2 is a transverse sectional view thereof taken on line 2-2 of Fig. 1; Fig. 3 is an enlarged longitudinal sectional view of a portion of the conveyer 75 and one of its supporting wheels; and Fig. 4 is an inverted view of several links of the conveyer.

Referring to the drawing the numerals 8 and 9 indicate two of the supporting standards of the conveyer of the book stitching machine which are of approximately inverted Y-form. The upper end of the forward standard 8 carries a sprocket wheel 10 and the rear standard 9 carries a chain 85 tightener frame 11 which is provided with sprocket wheels 12 and 13. The tightener frame is provided with two horizontally projecting threaded bolt members 14 which extend through openings 15 in the standard 90 and have nuts 16 threaded on the bolt members on opposite sides of the said standard.

The sprocket wheel 10 is journaled in a slotted bearing 17 to permit the said wheel to accommodate itself to the links of the 95 conveyer.

A guide bar 18, rectangular in cross section, extends from one standard to the other and is mounted on the upper ends thereof in alignment with the upper sprocket wheels. 100 The improved conveyer 19 which rides on this guide bar comprises pairs of spaced link members 20 having inwardly extending offset portions 21 on one end which are overlapped by the adjacent straight end portions 105 22 of the adjacent link members. The overlapped portions are pivoted together by pivot pins 23 which are provided with a medial enlargement 24 to space the offset portions of the link members apart to accommodate the teeth of the sprocket wheels. 110 These medial enlargements may be formed

integral with the pins or may be in the form of sleeves slipped over the pins and positioned between the links.

Each pair of link members are provided with a cover 25 of inverted V-form in cross section and having side portions which project below the said members to form guide extensions 26 which co-act with the guide bar to hold the conveyer in proper position to receive, support and carry the groups of leaves to the stitching portion of the machine (not shown).

Each fifth hood is provided with an upwardly and outwardly projecting pin 27 and between these pins the leaves to be bound in groups are placed.

The hood extensions are of angular formation or beveled at the corners as indicated by the numeral 28 to permit the link members to turn at their pivotal connections when traveling over the sprocket wheels.

The hoods are of sufficient length to contact with each other along their front and rear edges when traveling on the guide bar so that a smooth surface is provided for holding the leaves.

In order to support the lower returning portion of the conveyer a supporting bar 29 is provided which has a V-shaped groove 30 to accommodate the apexes of the hood and also a beveled face 31 to compensate for the angle of the pins 27. This supporting bar extends between the diverging legs of the standards.

In operation it is only necessary to drop the groups or sets of leaves on the hood portions of the conveyer and they will be carried to the stitching mechanism without coming into rubbing contact with other parts of the conveyer and consequently will lie smooth and evenly on the hoods and preserve their aligned position with relation to each other when stitched.

From the foregoing description it will be seen that the conveyer for book stitching machines is of simple construction and is well adapted for the purpose described.

What I claim as my invention is:

1. A conveyer for a book stitching machine, comprising a supporting means, an endless belt carried thereon, and a plurality of hood members extending over one portion of the belt and below the belt to form a smooth uninterrupted sheet supporting wall on the portion of the belt traveling in its upper path of travel.

2. A conveyer for a book stitching machine, comprising a supporting means, an endless chain carried thereon, and a plural-

ity of hood members connected to the links of the chain and extending over the upper portions of the links when traveling in its upper path of travel and having extensions forming guides which project below the links to form side guides for engaging a support upon which the chain travels.

3. A conveyer for a book stitching machine, comprising a supporting means, an endless chain carried thereon, and a plurality of V-shaped hoods extending over three sides of the chain links and having downwardly projecting extensions to form side guides for engaging a support upon which the chain travels.

4. A conveyer for a book stitching machine, comprising a supporting means, a guide bar carried thereon, an endless chain supported in part on said bar, and a plurality of hoods carried by the chain and extending in inverted V formation over the portion of the chain resting on the bar and projecting downwardly on both sides of the bar.

5. A conveyer for a book stitching machine, comprising a supporting means, an endless chain carried thereon, a plurality of V-shaped hoods extending over three sides of the chain links and having extensions to form side guides, and pins projecting from some of the hoods.

6. A conveyer for a book stitching machine, comprising a supporting means, a guide bar carried thereon, an endless chain supported in part on said bar, a plurality of hoods carried by the chain and extending in inverted V formation over the portion of the chain resting on the bar and projecting downwardly on both sides of the bar, and pins projecting from some of the hoods.

7. A conveyer for a book stitching machine, comprising a supporting means, an endless chain supported thereon and formed of pairs of spaced link members having inwardly extending offset portions which are overlapped by the straight end portions of adjacent pairs of links, pins extending through the overlapping portions, a V-shaped hood covering a plurality of sides of each pair of link members and having extension forming side guides, and pins projecting from some of the hoods.

In testimony whereof, I affix my signature, in presence of two witnesses.

MARTIN CHRISTENSEN.
